UNITED STATES PATENT OFFICE

HERBERT G. KUECHLE, OF MILWAUKEE, WISCONSIN, ASSIGNEE, BY MESNE ASSIGNMENTS, TO I-X-L METAL SPRING COVER COMPANY, OF MILWAUKEE, WISCONSIN, A CORPORATION OF WISCONSIN

SPRING COVER

Application filed December 4, 1929. Serial No. 411,441.

This invention pertains to spring covers, and more particularly to metal covers adapted to be folded and locked upon a leaf spring to snugly engage the same and effect 5 a complete housing therefor.

The invention has primarily for its object to simplify and otherwise improve the present structures by the provision of an exceedingly simple one-piece cover, easily 10 folded and locked upon a spring and affording sufficient flexure to compensate for the action of the spring, thus materially reducing both the cost of manufacture and installation.

Incidental to the foregoing, a more specific 15 object of the invention resides in the provision of a spring cover unit formed from a single blank of sheet metal locked upon the spring to snugly enclose the same, and folded transversely upon itself to provide the necessary flexure for the action of the spring.

A still further object is to provide a cover 20 of the foregoing character, in which the sides and bottom of the cover are cut transversely intermediate the ends of the cover to provide overlapping engagement of the same, while the connecting top web of the cover, adjacent the slotted sides, is folded transversely upon 25 itself to provide a hinge.

With the above and other objects in view, which will appear as the description proceeds, the invention resides in the novel construction, combination and arrangement of parts substantially as hereinafter described 30 and more particularly defined by the appended claims, it being understood that such changes in the precise embodiment of the herein disclosed invention may be made as come within the scope of the claims.

In the accompanying drawing is illustrated 35 one complete example of the physical embodiment of the present invention constructed according to the best mode so far devised for the practical application of the principles thereof.

In the drawing, Figure 1 is a side elevation of a conventional semi-elliptic spring with a cover constructed in accordance with the present invention applied thereto, parts being broken away and in section to more 50 clearly illustrate structural features;

• Figure 2 is a bottom plan elevation with parts broken away and in section;

Figure 3 is a fragmentary view of the blank prior to folding the same upon the spring; 55

Figure 4 is a transverse section taken on the line 4—4 of Figure 1;

Figure 5 is a fragmentary elevation illustrating the hinged portion of the cover; and

Figure 6 is a detail section taken on the 60 line 6—6 of Figure 1 illustrating one method of locking the cover on a spring.

Referring now more particularly to the accompanying drawing, the numeral 1 designates a conventional semi-elliptic spring comprising a top leaf 2 provided at its extreme ends with the usual eyes 3. Underlying the top spring leaf 2 are a plurality of progressively shorter leaves 4 which are secured together by the U-bolts 5 which straddle the 65 leaves and secure the same to a spring saddle 6, the latter usually forming a part of the axle of the vehicle.

From the foregoing, it will be noted that the laminated spring 1 is capable of vertical 75 flexure when the weight of the vehicle is placed upon the eyes 3, and in such action the leaves will necessarily engage one another throughout their entire length and have a relative longitudinal movement as the spring 80 is flexed.

The present invention, which aims to reduce manufacturing costs to a minimum, and also simplify the operation of assembling a metal cover on a spring, provides a one-piece 85 cover 7, preferably formed from a single blank of sheet metal of any desired length, depending upon the spring to which the same is to be applied.

Due to the fact that the cover must have a 90

certain amount of flexure to compensate for the vertical action of the spring. The blank from which the cover is formed is slotted or cut out transversely at 8, leaving a longitudinal connecting web 9, which, when assembled upon a spring, extends across the entire width of the top of the spring. It will thus be noted that the cut out portions 8 extend only through the sides and bottom of the cover.

10 In manufacture, the blank may be bent longitudinally along the dotted lines 10 to facilitate forming the same about the spring, while the longitudinal edges may be folded back upon themselves along the lines 11 to

15 provide interengaging lips 12 for locking the cover on the spring, as best shown in Figure 4.

Prior to assembling the cover on the spring, the web 9, extending the entire width 20 of the top portion of the cover, is folded upon itself transversely along the dotted lines 13 in Figure 3, thus forming the flexible hinge 14, as best shown in Figures 1 and 5.

In folding the web 9 upon itself, it will be 25 seen that the adjacent cut-out edges 8 of the sides and bottom of the cover, will be brought into overlapping engagement to provide a secure joint between the cut-out portions, as best shown in Figures 1 and 2. Obviously, 30 in forming the cover, as many hinges as necessary can be provided, depending upon the length of spring to be covered. In the conventional spring illustrated, two folds or hinges are provided, but this number may 35 be readily increased or reduced, depending upon the length of spring and the amount of action required of the same.

In assembling the cover upon a spring, the longitudinal bottom portions are overlapped 40 and the lips 12 brought into interlocking engagement to secure the cover on the spring, as best shown in Figure 4. However, it is to be understood that various means may be employed for securing the overlapped longitudinal edges of the cover together, such as 45 for instance, welding, rivetting, or the like.

Due to the fact that the sides and bottom 50 of the cover are brought into overlapping engagement, when the cover is assembled upon a spring, the interengaging tongues 12 must also overlap and, therefore, one of the bottom seams is bent downwardly, as shown at 55 15 in Figure 5, to receive the adjacent seam 16.

From the foregoing, it will be noted that 55 a very simple and inexpensive cover has been provided which can be readily assembled upon a spring with a minimum effort, thus materially reducing both the cost of manufacture of the cover and installation of the same.

60 At the present time, the majority of metal covers in use comprise not only a plurality of sections, but each sectional unit consists of a plurality of elements. Thus, in assembling the cover on a spring, the operator is required to 65 handle numerous parts of different sizes

which must all be assembled in correct relative positions, thus requiring a high degree of precaution and consuming considerable time, which is an important item in present production methods, particularly the automobile industry where assembling is effected through 70 continuous, progressive operations.

In operation, it will be quite apparent that the folded hinge 14, in cooperation with the overlapping sides and bottoms of the cover, provides a flexure which will readily compensate for the vertical action of the spring and at the same time affords an especially 75 tight and secure housing.

While the same forms no part of the invention, it is to be understood that in assembling the cover upon a spring, the spring may first be wrapped with the usual lubricant retaining fabric or cover, thus insuring proper lubrication of the spring, as well as completely 80 housing the same against moisture and dirt.

I claim:

1. A one-piece metallic spring cover adapted to snugly fit the top, sides and bottom of a spring, and provided with a transverse fold 90 in its top portion intermediate the ends to compensate for vertical flexure of the spring and cause the adjacent portions of the cover to overlap transversely in alinement with said fold, and having its longitudinal edges 95 secured together along the bottom of the spring.

2. A one-piece metallic spring cover adapted to snugly fit the top, sides and bottom of a 100 spring and provided with a transverse fold in its top portion intermediate the ends to compensate for vertical flexure of the spring, and having its remaining portions overlapping each other in transverse alinement with 105 said fold, and means for securing the longitudinal edges of said cover together along the bottom of the spring.

3. A one-piece metallic spring cover adapted to snugly fit the top, sides and bottom of a 110 spring and provided with a transverse fold in its top portion intermediate the ends to compensate for vertical flexure of the spring, the side and bottom portions of said cover being cut transversely in alinement with said 115 fold and the adjacent portions being overlapped upon each other, and means for securing the longitudinal edges of said cover together along the bottom of said spring.

4. A one-piece metallic spring cover adapted to snugly fit the top, sides and bottom of a 120 spring and provided with a transverse hinge in its top portion intermediate the ends to compensate for vertical flexure of the spring, said hinge being formed by folding the top portion back upon itself, the side and bottom portions of the cover being 125 cut transversely and the portions adjacent said cut being overlapped, and means for securing the longitudinal edges of said cover together along the bottom of the spring.

5. A spring cover adapted to snugly fit the top, sides and bottom of a spring and formed from a single blank of sheet metal and provided with a transverse fold in its top portion intermediate the ends of the blank to compensate for vertical flexure of the spring and cause the adjacent portions of the cover to overlap transversely in alinement with said fold, and having its longitudinal edges secured together along the bottom of the spring.

6. A spring cover adapted to snugly fit the top, sides and bottom of a spring and formed from a single blank of sheet metal and provided with a transverse fold in its top portion intermediate the ends of the blank to compensate for vertical flexure of the spring, the side and bottom portions of said cover being cut transversely in alinement with said fold and the adjacent portions being overlapped upon each other, and means for securing the longitudinal edges of said cover together along the bottom of said spring.

7. A spring cover adapted to snugly fit the top, sides and bottom of a spring and formed from a single blank of sheet metal and provided with a transverse hinge in its top portion intermediate the ends to compensate for vertical flexure of the spring, said hinge being formed by folding the top portion back upon itself, the side and bottom portions of the cover being cut transversely and the adjacent portions overlapping each other in alinement with said fold, and means for securing the longitudinal edges of said cover together along the bottom of the spring.

8. A spring cover adapted to snugly fit the top, sides and bottom of a spring and formed from a single blank of sheet metal having its side and bottom portions cut transversely, the top portion of said cover being folded back upon itself adjacent said cuts, causing the side and bottom portions of the cover adjacent said cutout portions to overlap each other, and means for securing the longitudinal edges of said cover together along the bottom of the spring.

9. A cover for a vehicle spring consisting of a single sheet of metal formed channel-shaped for embracing two sides and both edges of the spring, means for providing overlap of the metal along the edges of the spring, and one side, said free edges of the channel being locked together to hold the cover on the spring.

10. In a spring cover comprising a single piece of metal, an uninterrupted web portion and having portions of its side overlapping when in a straight line position and adapted to maintain said overlapping relation under spring flexures to either side of normal position.

11. A one-piece metal cover for vehicle springs comprising a central portion to over-

lie one side of the spring and having a plurality of edge sections formed from the central portion in overlapping relationship, said edge sections on opposite edges of the spring being wide enough so as to bend over and cover the other side of the spring, and means for locking the initial free edges together.

In testimony that I claim the foregoing I have hereunto set my hand at Milwaukee, in the county of Milwaukee and State of Wisconsin.
